UNITED STATES PATENT OFFICE.

CHARLES ELLSWORTH MCCORMICK, OF LEXINGTON, KENTUCKY, ASSIGNOR TO
MERCURY BODY CORPORATION, OF LEXINGTON, KENTUCKY.

AUTOMOBILE.

1,360,656.

Specification of Letters Patent. Patented Nov. 30, 1920.

Application filed March 18, 1920. Serial No. 366,901.

To all whom it may concern:

Be it known that I, CHARLES E. MCCORMICK, a citizen of the United States, and a resident of Lexington, in the county of Fayette and State of Kentucky, have invented certain new and useful Improvements in Automobiles; and I do hereby declare the following to be a full, clear, and exact description of the invention, such as will enable others skilled in the art to which it appertains to make and use the same.

This invention relates to improvements in automobiles and more particularly to the body portion thereof, one object of the invention being to provide features whereby a Ford car may be so modified in appearance and so improved structurally as to combine simple, comfortable and substantial qualities with pleasing streamline effects.

With this and other objects in view, the invention consists in certain novel features of construction and combinations of parts as hereinafter set forth and pointed out in the claims.

In the accompanying drawings; Figure 1 is a side elevation showing a car embodying my improvements; Fig. 2 is a plan view; Fig. 3 is a longitudinal section; Figs. 4, 5, 6, 7, 8, 9, 10, 11, and 12 are detail views of parts of the sheet metal body, and Figs. 13, 14, 15 are views of certain details.

1 represents the underframe or chassis, the rear portion of which comprises bent beams 2 connected by a cross beam 3,—said bent frame beams being so formed that the major portion of the chassis shall be disposed in a lower plane than the plane of the rear portion thereof. In constructing the underframe 1, I may employ a "Ford" chassis from which the rear portions of the side bars and rear connecting beam have been removed, and the parts so removed will be replaced by the bent beams 2 and cross beam 3. The effect of the employment of the added bent beams 2 will be to lower the major portion of a Ford chassis, and the forward end of the latter is suitably supported by and connected with a forward axle, while the rear cross bar 3 is suitably connected, through the medium of a rear spring 5 with the rear axle.

The underframe or chassis supports a wooden body frame comprising longitudinal beams 7, 7, and cross members 8,—the rear ends of the longitudinal beams 7 be-

ing supported by and suspended from the rear cross bar 3 of the chassis through the medium of Z-brackets 9, and the said wooden body frame supports a sheet metal body 10 as hereinafter described.

The body 10 comprises main side members 11, a rear top member 12, a rear bottom member 13, forward supplemental side members 14, and a front end member 15, and these members, with the hood portion 16 65 constitute the sheet metal body of the car.

The main side members 11 taper toward the rear end of the body and portions of the tapering part of these members are rounded. The forward portion of each member 70 11 is made with an upward extension 18 having a rear curved and beveled edge 19. The upper portions of the extension 18 of the two side members 11 are so bent as to form the transversely curved top of the 75 body in front of the seat 20,—the edges 21 of said extensions being brought together and welded. The lower portion of each member 11 is cut away as indicated at 22 for the accommodation of a supplemental forward side member 14. Each member 14 has the form shown in Fig. 9 and is bent on the lines 24 and 25. The flange 26 formed at the rear end of the member 14 is secured to a flange 27 at the rear end of the cut-away 85 portion 22 of the member 11 while the bent-over portion or flange 28 overlies the wooden body frame and is welded to a flange 29 of the member 11. Both flanges 28 and 29 are secured to the wooden body frame by suitable fastening means.

Rearwardly of the upward extensions of the members 11 of the body, said members are connected with the wooden body frame by means of clips 30, 31, which are welded 95 to said side members and securely fastened to wooden body frame.

A dash board 32 is located at the forward ends of the members 11 and is secured thereto. The front member 15 of the body is 100 secured at the forward ends of the supplemental side members 14 and between said front member and the dash board, the engine hood 16 is located,—said hood being provided with hinged sections as is customary.

The rear top member 12 of the tail portion of the body has a general tapering or oval form and is welded at its edges to the upper edges 34 of the tapering portions of the 110

members 11, while the edges of the bottom rear member 13 are welded to the edges 35 of the members 11. The rear or tail portion of the body is reinforced and stiffened by 5 a bulkhead 36 having flanged edges welded to the members of said rear or tail portion.

A bar 37 (which may be made from an old Ford rear axle) is connected at its forward end with the rear cross bar of the chassis 10 and extends rearwardly through the rear end of the tail portion of the body,—the rear projecting end 38 of said bar or axle serving as a mounting for a spare wheel. The bar 37 also serves to protect the sheet 15 metal body in the event of a rear end collision.

Each side member 11 of the body is slotted as at 39 for the accommodation of the rear axle, and these side members are 20 also provided with openings 40—41 for the accommodation of brace rods 42—43. A slot 44 may be made in each member 11 to permit the passage of steps 45, the latter being secured to the wooden body frame as 25 shown in Fig. 2.

The top member of the tail portion of the body may be provided with an opening, closed by a door 46 and said top member may also be provided with an opening 47 to 30 receive the extension 48 of a gasoline tank 49,—the latter being mounted on the rear portion of the chassis.

To more particularly describe the metal body shell, with respect to its shape, it may 35 be stated that the surface of said body shell, from its rear end to a plane approximately fifty-four inches therefrom and perpendicular to the longitudinal axis, is of a shape to greatly decrease the unavoidable head-on 40 air resistance of the car. This portion of the surface of the metal body shell is formed by a combination of ellipses and parabolas, the relation of which can be best explained by reference to Figs. 4, 5 and 12. The side 45 view (Fig. 12) of the upper and lower tail members shows them relatively placed as they will be after assembly with the main side member 11 (Fig. 4). Referring now to Fig. 12, let it be assumed that the lines 50 marked "Axis of parabolas, plane A" and "Top of frame, plane F," are two horizontal and parallel planes two inches apart. Let it also be assumed that the center line marked "Plane V" on the plan view of the 55 top tail member, Fig. 4, is a vertical plane perpendicular to planes A and F. Plane V contains two semi-parabolas whose origins and axes are coincident respectively, the common axis lying in plane V. The projection 60 of the upper tail member upon plane A is a portion of an ellipse, the dimensions of which may be 39 inches by 108 inches and which has its center in the axis of parabolas and 54 inches from their origin. These 65 three curves are the loci of the generating

cross section as it moves always perpendicular to the axis of parabolas, thereby forming the upper tail piece. The cross section at any given point is a semi-ellipse, the length of whose major axis is the same as 70 the width of the plane A ellipse taken at that particular point, and the length of its semi-minor axis is determined by the distance between the two parabolas measured perpendicular to plane A. The surface of the 75 lower tail member is cylindrical and is formed along its circumference and perpendicular to the plane of a quarter-ellipse 8 inches by 28 inches which lies in the vertical plane V and has its semi-major axis 80 parallel to and two inches from the axis of parabolas. This last surface described and the intervening surface between the upper and lower tail members, are portions of the surface of right elliptical cylinders, the first 85 surface having its elements horizontal, and the intervening surface having its elements perpendicular.

The construction of the underframe herein shown and described is not specifically 90 claimed herein but is embodied in application for patent filed by me on even date here-with.

Various changes might be made in the details of construction of my invention without departing from the spirit thereof or limiting its scope and hence I do not wish to restrict myself to the precise details herein set forth.

Having fully described my invention what 100 I claim as new and desire to secure by Letters-Patent, is:—

1. A sheet metal automobile body comprising side members having tapering tail portions, a top tail portion having a partly 105 elliptical outline and a partly elliptical cross-section and secured at its edges to the upper edges of the tapering tail portions of said side members, and a bottom tail portion having a partly elliptical outline and 110 curved longitudinally, said bottom tail member secured to lower edges of the tapering portions of said side members.

2. A sheet metal automobile body, comprising side members having tapering rear 115 portions, a top tail member curved transversely and welded at its edges to upper edges of said side members, a bottom tail member curved longitudinally and welded at its edge to lower edges of said side members, and a bulkhead disposed within the body and welded to the tail portions thereof.

3. A sheet metal automobile body comprising side members having rear tapering portions and forward upward extensions, 125 said upward extensions bent and coöperating to form a forward top portion, a top tail member curved transversely and secured at its edges to the upper edges of the tapering side members, and a bottom tail member 130

curved longitudinally and secured at its edges to lower edges of the tapering portion of said side members.

4. An automobile body structure comprising a body frame and a sheet metal shell, said shell comprising side members and top and bottom tail members secured to said side members, and clips welded to said side members and secured to said body frame.

10 5. An automobile body structure comprising a body frame, and a sheet metal shell, said shell comprising side members having upward extensions at their forward ends bent and coöperating to form a forward top portion, and top and bottom tail members secured at their edges to upper and lower edges of said side members, and means securing said side members to the body frame.

6. In an automobile structure, the combination with a chassis, a wooden body frame, and brackets connecting the rear end of the body frame with the rear end of the chassis, of a sheet metal body comprising side members having tapering rear portions and forward upward extensions bent and coöperating to form a forward top portion and top

and bottom tail portions secured at their edges to upper and lower edges respectively of the tapering portions of said side members, and a bar connected with the rear end 30 of the chassis and extending to the rear end of the tail portion of the sheet metal body.

7. An automobile body structure, comprising a body frame, and a sheet metal body comprising side members having forward 35 upward extensions bent and coöperating to provide a forward top portion, said side members having rearwardly extending tapering portions and said side members having forward cut-away portions, supplemental 40 side members located at said cut-away portions of the first-mentioned side members and secured to the latter and to the body frame, a front member at the forward ends of said supplemental side members, and top 45 and bottom tail members secured at their edges respectively to the upper and lower edges of the tapering portions of said first-mentioned side members.

In testimony whereof, I have signed this 50 specification.

CHARLES ELLSWORTH McCORMICK.
